TO UNIVERSAL AUTOMATIC ELECTRIC SIGNALING COMPANY, OF LA CROSSE, WIS-
CONSIN, A CORPORATION OF WISCONSIN.

THERMOSTAT.

1,031,847.

Specification of Letters Patent.

Patented July 9, 1912.

Application filed May 22, 1911. Serial No. 628,872.

To all whom it may concern:

Be it known that I, JOHN S. HARLEY, a citizen of the United States, residing at Minneapolis, in the county of Hennepin and State of Minnesota, have invented certain new and useful Improvements in Thermostats, of which the following is a specification.

My invention relates to an improved thermostat which when placed in a circuit will operate normally to close said circuit, but which in case of fire will respond to a comparatively low degree of heat to break the circuit whereby an alarm may be signalled through mechanism set in operation by the breaking of said circuit.

In fire alarm systems it is desirable that the detection means shall be such that not only will the presence of fire be unfailingly signalled but also other abnormal conditions which would render the system inoperative such as the breaking of wires. To obtain such desired results it has been found that a system involving a closed circuit, such for example as that described in my application Serial Number 628,873, dated May 22, 1911, for fire alarm systems, is essential, the operation of the alarm signaling device following the breaking of such closed circuit.

To provide means for breaking such a circuit very promptly upon the occurrence of a fire I have invented the thermostat herein described. The principles upon which this thermostat operates are fundamentally the provision of a member in the circuit normally closing said circuit, part of said member forming part of said circuit consisting of a mobile conducting liquid held in position by some substance fusible at a comparatively low temperature so that when the fusible substance is melted by the first heat of the fire the conducting liquid will flow from the thermostat thereby breaking the circuit.

The full objects and advantages of my invention will be given in connection with the detailed description thereof and are particularly pointed out in the claims.

In the drawings illustrating one form of my invention,—Figure 1 is a sectional view of my improved thermostat. Figs. 2 and 3 side and elevation views, respectively, of a form of the thermostat attached to a wall. Figs. 4 and 5 show another form of connect-

ing means for placing the thermostat in position so that the opening will certainly be turned down. Figs. 6 and 7 are detail views of the same securing means. Fig. 8 is a section on line 8—8 of Fig. 1. Fig. 9 is a side sectional view of the contact spring for securing the thermostat in position.

My thermostat comprises a tubular body portion 10 of fiber, rubber, glass or other non-conducting material having extending within the same at each end thereof metal pins 11, 12, each pin being provided with a curved head 13 and extending within the tubular member 10 to a distance less than one-half the length thereof so that there will be an intervening space 14 between the ends of the pins 11 and 12. The space 14 will be filled with mercury or any other mobile conducting liquid which by contact with the ends of the pins 11 and 12 will provide means for closing any circuit in which the thermostat may be used. Upon one side of the body portion 10 opposite the cavity 14 an opening 15 is formed which may be of any desired shape, the circular or slightly oval shown being found very satisfactory. I have also found it to be effective for the purpose intended to bevel the walls of said opening inwardly, as shown at 16.

Before assembling the pins 11 and 12 and the conducting liquid within the tube 10 the inner walls thereof are preferably waxed or covered with a thin layer of grease, and when the mercury or other liquid has been placed within the cavity 14 the opening 15 from said cavity is sealed with a layer of readily fusible material, as shown at 17. For this purpose I have found ordinary tallow to be very satisfactory, but the use of other fusible substances which will melt at the desired temperature to release the mercury or liquid from the cavity is contemplated by me and falls within the scope of my invention.

My thermostat may be formed with both heads 13 semi-spherical, as shown in Fig. 2, and may be held within the circuit by spring arms 18 and 19 of a bridge 20 secured to the wall or ceiling in the ordinary way. The spring arms 18 and 19 will each be formed with a cavity or depression 21, as shown in Fig. 9, said cavities coöperating with the heads 13 of the thermostat to hold the same

in position and provide the contacts for completing the circuit. I do not, however, limit myself to the use of a thermostat with a bridge, since it is practicable and falls 5 within the scope of my invention to connect my thermostat directly to the wires of a circuit without the use of any bridge, and since the tubular portion 10 of my thermostat is non-conducting I may secure said 10 thermostat directly to the walls or ceiling of a room and the wires directly to the ends of the thermostat. It is, however, essential to the operation of my device that wherever the thermostat may be placed the opening 15 shall be faced directly downwardly. To render it impossible to place the thermostat in any other position, the attaching means shown in Figs. 1 and 4 to 7, inclusive, may be used. In this form, in place of the 20 spring metal contact strip 19, a longitudinally positioned strip 22 is used having a bifurcated upper end 23 provided with a side slot 24. Extending from one of the heads 13 is a flat member 25 having a right-angled bend 26 adapted to seat within the slot 24 when the thermostat is placed in the 25 circuit. As the slot 24 is at one side only the position of the bend 26 is such as to make it impossible to assemble the thermostat in the bridge in any position excepting with the opening 15 turned down. The 30 relative position of the bend 26 with respect to the opening will, of course, have to be varied to adapt the thermostats to be attached either to the walls or ceiling.

In use my improved thermostat being positioned in a circuit with the opening 15 turned down will maintain the circuit closed under normal conditions. Should, 40 however, a fire occur at any point near where the thermostat is located, the first rise in temperature resulting therefrom will melt the fusible seal 17, whereupon the mercury or other conducting liquid within the cavity 45 14 will run out through the opening 15 thus breaking the circuit and causing the signaling means to operate. By reason of the fact that the inner wall of the tubular member 10 is waxed or greased all of such liquid 50 conductor will instantly leave the cavity 14 so that the circuit will unfailingly be broken.

My improved thermostat can be made very cheaply and assembled in a circuit with

the greatest ease so that a large number of 55 such thermostats may economically be placed in each room or department of the building protected by the fire alarm signaling system. The thermostats cannot get out of repair and, although responsive with 60 extreme rapidity to a rise in temperature above the fusing point of the wax or grease seal 17, are not sensitive in any other particular and therefore are peculiarly free from becoming inoperative or operating im- 65 properly on account of conditions other than those relating to temperature.

I claim:

1. A thermostat comprising a tube of non-conducting material, conducting members 70 entering the tube at each end thereof and filling the said tube except for a space between the separated ends of said conductors, said cavity being filled with mercury and opening through the wall of said tube, a 75 fusible seal closing said opening, a bridge for receiving said thermostat comprising a slotted contact, and an extension plate on at least one of said conducting members having a member for engaging said slot 80 whereby the thermostat will be positioned in the circuit with the opening facing downward.

2. A thermostat comprising an open-ended smooth-walled tube of non-conducting material having a centrally positioned opening through the wall thereof, said opening being round or oval in form and having inwardly beveled sides, the inner walls of 85 said tube being coated with grease or wax, 90 conducting members extending within the tube at each end thereof and filling the same to a point near the edges of said opening so as to leave a cavity into which the opening extends and of substantially the same length 95 as the longer diameter of said opening, said cavity being filled with mercury, and a seal of readily fusible material normally held in position to close said opening and retain the mercury within the cavity by the beveled 100 sides of said opening.

In testimony whereof I affix my signature in presence of two witnesses.

JOHN S. HARLEY.
